ROTARY SLIDE RULE CALCULATOR

Allen R. Herron, Los Angeles, Calif.
(17656 Orna Drive, Granada Hills, Calif. 91344)

Filed June 21, 1972, Ser. No. 264,806

Term of patent 14 years

Int. Cl. D19—99

U.S. Cl. D52—6 B

FIG. 1 is a top plan view of a rotary slide rule calculator, showing my new design;

FIG. 2 is a side elevational view thereof.

The back or bottom, not shown, is plain and unornamented.

I claim:

The ornamental design for a rotary slide rule calculator, substantially as shown and described.
